[57] CLAIM

The ornamental design for a multiple-station fitness center, as shown and described.

DESCRIPTION

FIG. 1 is a perspective view of a multiple-station fitness center showing my new design;

FIG. 2 is a bottom plan view thereof shown on a slightly reduced scale;

FIG. 3 is a top perspective view thereof shown partially in fragment and on an enlarged scale;

FIG. 4 is a perspective view of one of corners shown partially in fragment;

FIG. 5 is a perspective view of a modified form of the design shown in FIGS. 1 through 4;

FIG. 6 is a bottom plan view thereof shown on a slightly reduced scale;

FIG. 7 is a top perspective view thereof shown partially in fragment and on an enlarged scale; and

FIG. 8 is a perspective view of one of the corners shown partially in fragment.
